UNITED STATES PATENT OFFICE.

JACOB B. BLAW, OF PITTSBURG, PENNSYLVANIA, ASSIGNOR TO BLAW COLLAPSIBLE STEEL CENTERING COMPANY, OF PITTSBURG, PENNSYLVANIA, A CORPORATION OF NEW JERSEY.

MOLD.

933,017.

Specification of Letters Patent. Patented Aug. 31, 1909.

Application filed March 17, 1908. Serial No. 421,716.

To all whom it may concern:

Be it known that I, JACOB B. BLAW, a citizen of the United States, residing at Pittsburgh, in the county of Allegheny and State of Pennsylvania, have invented certain new and useful Improvements in Molds, of which the following is a specification.

The invention relates to sheet metal molds for use in the construction of sewers, conduits and similar passages, and has for its principal objects; the provision of an improved type of framework especially suitable for molds of large diameter and one wherein the thin shell is properly supported with a framework of minimum weight; and the provision of a rigid mold framework which may be conveniently and readily collapsed to permit the freeing of the shell of the mold from the concrete. One embodiment of the invention is illustrated in the accompanying drawings, wherein:

Figure 1 is an end view of the mold.

Figure 2 is a longitudinal section on the line II—II of Figure 1,

Figure 3 is a partial transverse section through the mold,

Figure 4 is an enlarged detail view showing the manner of attaching the securing orackets,

Figure 5 is an enlarged detail section illustrating the manner of securing the two half shells together, and

Figure 6 is an end view of the securing means shown in Figure 5.

The form of mold shown and hereinafter described is intended primarily for the formation of large concrete sewers or passages, and the invention resides particularly in the form of supporting framework, whereby a rigid mold form is secured, and which permits at the same time the use of light sheet metal as the outer surface or shell of the mold, to the end that a very large mold may be made sufficiently light to be easily handled and moved from one position to another on the rollers or wheels shown. Briefly stated the invention consists in making the mold in two parts or shells secured together at their upper edges, trusses or framework for rigidly supporting each of the halves independently of the other half, and means for moving the lower portion of the mold sections toward and from each other a certain distance, so that the mold shell may be freed from the concrete after it has set.

The shell of the mold consists of the plates 1—1 secured to the circumferential stiffening channels 2 and 3, (Fig. 2), which channels terminate at the upper central portion of the mold and are secured together at this point by means of the securing members shown in Figs. 5 and 6 to be hereinafter described. The channels 2 are riveted to the plates, but the channels 3 are secured detachably to the shell by the means shown in Figure 2. As here shown the plates constituting the shell come together or abut at the backs of the channels and are provided at a short distance back from the edges with the angles 5, which are riveted to the plates. These angles 5 are detachably secured to the flanges of the channels by means of the bolts 6. The plates 1 constituting the shell are secured together along their horizontal edges by means of the angles 7 shown in Figure 3, which angles are riveted to the edges of the plates 1 and are secured together by means of bolts 8. The two halves which constitute the mold are secured together along the upper center line of the mold in the manner indicated in Figures 5 and 6. As here shown each of the channels 2 and 3 is provided with a securing angle or bracket 9, which bracket opposes a similar bracket upon the opposing channel as indicated in dotted lines in Figure 5. A liner plate 10 extending the length of the mold section is interposed between the flanges of the two angles 9—9 and these parts are secured together detachably by means of transverse bolts. Each half of the mold is braced and supported by means of a truss construction including the inclined angles 11, the horizontal angles 12, and the plurality of transverse braces 13, 14, 15, 16 and 17. The opposing inclined angles 11 are braced and supported upon each other by means of the braces 18, which are preferably of wood and are each provided at the end with a turn-buckle 19 for expanding the shell to its proper position and subsequently contracting it to free it from the concrete after such concrete has set. The ends of these braces 18 are detachably secured to the angles 11 by means of bolts 20 passing through such ends and through the angles 20 secured to the angles. The inner ends of the transverse braces 12, 13, 14, 15, 16 and 17 are secured to the angles 11 by means of the gusset plates 21 in the manner 110

shown, and the outer ends are secured to the shell by means of the gusset plates 22, which gusset plates are secured to the inside of the angles 3 as indicated in Fig. 4, small angles 22 being riveted to the gusset plates and channels respectively. Brackets 23 are secured to the angles 12 for carrying the supporting wheels 24, while the I beams 25 carry the wheels 26. The I beams extend longitudinally the length of the mold and serve to materially stiffen it. The angles 20 also extend the length of the mold and serve to tie the various trusses together. It will be seen from the foregoing that each half of the mold is very rigidly and securely braced independently of the other side, and that the two sides may be moved a certain distance by means of the collapsing braces 18. By the use of the truss arrangement with its transverse braces, and because of the secure stiffening of the shell by means of the angles 2 and 3, a very thin plating may be used and the total weight of the mold be made very much less than would be the case if the bracing and stiffening were less secure and heavier plates had to be used for the shell of the mold.

In operation the mold section is supported upon jacks with the wheels 24 and 26 about six inches above the track upon which they are designed to run, and the turnbuckles 19 are operated to spread the two halves of the mold to their proper positions. Concrete is then applied over the mold section to the desired thickness and allowed to set. After the concrete has set, the turnbuckles 19 are operated to bring the sides of the mold inward and free it from the concrete. Only a slight movement is necessary in order to secure this result as the weight of the mold causes it to disengage itself after the shell of the mold has been slightly loosened from the engaging concrete. As each side of the mold is rigidly braced the point of yielding upon the contraction of the turnbuckles is the central longitudinal portion of the mold at which the angles 9 and

plates 10 are employed. After the mold has been slightly contracted and has dropped by its own weight so that the wheels 24 rest upon the tracks provided therefor, the mold is moved to a new position and the operation repeated.

Having thus described my invention and illustrated its use, what I claim as new and desire to secure by Letters Patent is the following:—

1. A mold consisting of a pair of opposing substantially triangular truss members connected at their upper ends in such manner that the lower portions of the truss members may be swung toward and from each other about the connection, and each comprising inner, outer, and bottom members, sheet metal lagging plates secured to the outer members of the trusses, transverse supporting means for said outer members extending to the inner members intermediate the ends thereof, and a collapsing brace between the lower portions of the truss members adapted either to maintain such members in their outer position or to draw them toward each other.

2. A mold consisting of a pair of opposing trusses supported by each other at their upper ends in such manner that the lower portions of the trusses may be swung toward and from each other, and each comprising an outer curved member, an inner member and a plurality of transverse stiffening members between said inner and outer members and connected to said inner member intermediate the ends thereof, sheet metal lagging plates secured to the outer sides of the outer truss members and transverse means adjacent the lower ends of said truss members for supporting and collapsing the same.

In testimony whereof I have hereunto signed my name in the presence of the two subscribed witnesses.

JACOB B. BLAW.
